UNITED STATES PATENT OFFICE

JAMES S. THOMPSON, OF NEW ROCHELLE, NEW YORK, ASSIGNOR TO FIREBAR CORPORATION, OF CLEVELAND, OHIO, A CORPORATION OF DELAWARE

GRATE BAR

Application filed June 25, 1931. Serial No. 546,772.

This invention relates to grate bars used for heavy duty purposes in locomotives, boiler furnaces, etc., and particularly those of the type which include a carrier, mounted on a frame or as part of a stoker, and a plurality of fuel-supporting units or finger bars removably mounted thereon. Specifically, the present invention is directed to the provision of such fuel-supporting units which are cheap, of light weight, and so constructed as to withstand the temperatures to which they are subjected without injury. The new units are particularly adapted for locomotive grate bars and an embodiment of the invention suitable for that purpose will be described in detail for purposes of explanation, though it is to be understood that the utility of the invention is not limited to that particular use.

At the present time, the weight of the grate structure has become a matter of considerable importance in the design and construction of locomotives, and certain railroads have substituted cast steel grate bars for the cast iron ones previously used, in order to reduce weight. Both cast iron and cast steel bars made in accordance with standard practise without side lugs are greatly affected by heat and require frequent replacement.

The present invention is, accordingly, directed to the provision of a grate bar which is lighter in weight per square foot of grate area than standard steel grate bars, and which is cheaper in cost and of much longer life.

The new bar comprises a carrier of any suitable construction and a plurality of fuel-supporting units thereon, each being hollow and formed of a single piece of sheet metal. Each unit resembles a closed box and it is of light gauge sheet stock, stiffened during the process of manufacture to resist distortion due to working stresses. In addition, each unit is formed to overcome difficulties which result from cumulative expansion. For this purpose the top of each unit which supports the fuel is, preferably, formed with convolutions or ribs, so that the expansion of different parts of the top takes place in different directions, and the sides of the units are simi-

larly corrugated or otherwise bent out of a plane to prevent cumulative expansion and to provide increased stiffness and rigidity.

Fig. 1 is a view in side elevation of one form of fuel-supporting unit constructed in accordance with my invention;

Fig. 2 is a sectional view on the line 2—2 of Fig. 1;

Fig. 3 is a fragmentary top plan view of the unit shown in Fig. 1;

Fig. 4 is a view in side elevation of a modified construction;

Fig. 5 is a fragmentary top plan view of the unit shown in Fig. 4;

Fig. 6 is a fragmentary section on the line 6—6 of Fig. 4;

Fig. 7 is a fragmentary section on the line 7—7 of Fig. 4;

Fig. 8 is a view in side elevation of another modified form of unit;

Fig. 9 is a partial sectional view on the line 9—9 of Fig. 8; and

Fig. 10 is a fragmentary plan view of the unit illustrated in Fig. 8.

Referring now to the drawing, the unit shown in Fig. 1 is made of a single piece of sheet steel and it is formed with a fuel-supporting top generally designated 11 and side walls 12 and 13. In the formation of the unit, the top 11 lies centrally of the blank and the side walls are bent at right angles to the top by suitable operations. Each side wall is provided with an edge flange 14 and, in the process of manufacture, the flanges are brought into edge contact and secured together by welding or the like. The flanges accordingly define a seam which extends from the point 15 at one end of the top along the edges of the remainder of the unit to the point 16 at the other end of the top. The end edges of each flange are brought into engagement with the end edges of the top at the points 15 and 16 forming a seam extending across each end of the unit, which seam is also closed by welding.

At its lower edge, the unit is provided with means by which it may be mounted on a carrier and in the construction illustrated, the unit is shown conventionally as having a recess generally designated 17 for the recep-

tion of the carrier. I do not intend that the unit is to be considered as necessarily having such a recess since in some grate bars of the carrier and finger bar type, the finger bar 6 or units have extending portions which enter recesses in the carrier and any suitable mounting of the units on the carrier can be employed, as desired.

It will be seen that the unit as described 10 has a top which supports the fuel and which is likely to be at a considerably higher temperature than the remainder of the unit and particularly the lower edge of the unit which lies close to the point where the air for combustion first strikes the unit. Provision is accordingly made to overcome cumulative expansion effects along the top and to this end, I provide the top of the unit in the construction illustrated with at least one rib or 15 ridge extending from one boundary of the top to the other. In the form shown in Fig. 1, the top has a plurality of transverse ridges 18 with intervening grooves 19. These ridges and grooves constitute corrugations and the 20 tops of the ridges serve as fuel supporting surfaces, while air for combustion may flow across the tops of the units in the grooves. With the top of the unit formed in this manner, expansion of different parts of the top 25 occurs in different and varying directions and as a consequence, the total expansion effect is broken up. The heating at the top of the unit, therefore, does not result in the top being distorted or the unit being bulged.

30 The provision of the transverse corrugations at the top of the unit serves also as a means for strengthening the top and similar means are employed to strengthen the side walls of each unit so that a lighter gauge of 35 metal may be employed than would otherwise be possible. In the construction illustrated in Fig. 1, the side walls are provided with beads 20 and as shown, these beads are interrupted in a direction across the unit. 40 They may be arranged regularly in rows as disclosed or an irregular spacing and arrangement may be adopted. The beads may be formed by bulging the metal outwardly or by forcing it inwardly, the latter construction 45 being illustrated in Fig. 2.

In some instances it may be desirable to 50 provide the unit with a top which is stiffened to a greater degree than obtainable by transverse corrugations, even though such increased stiffness involves a sacrifice of the 55 means for preventing cumulative expansion effects in a direction lengthwise of the unit. For increased stiffness I may provide the unit with a longitudinal rib 21 along its top 60 together with transverse corrugations 18 at somewhat greater intervals than are shown in Fig. 1. A unit having a top with a lengthwise rib and transverse corrugations 65 is illustrated in Fig. 4 and in that figure, I have also shown strengthening means for the

side walls, taking the form of beads 22 which extend completely across the unit so far as that is possible. It will be understood that this type of strengthening means for the side walls may be used with the top shown in Fig. 1 and similarly the strengthening means used in the unit illustrated in Fig. 1 may be employed with a top of the type shown in Fig. 4.

In Fig. 8 there is shown a unit which has 70 a top provided simply with a longitudinal rib 23 and having its side walls strengthened by two series of ribs 24 arranged at an angle to the top and intersecting one another. This arrangement of ribs sub-divides the surface 75 of the side walls into a plurality of diamond-shaped areas and the ribs extending in the different inclinations to the top provide great 80 stiffness for the side walls, in the directions in which stresses are applied in service.

In all of the constructions illustrated, the 85 units are provided with spacing projections 25 which may be formed on opposite faces thereof, one near each end, and serve to keep 90 the units spaced to permit air to flow up between the units.

In any of the units disclosed, the flat surfaces are so strengthened by ribs, corrugations, or the like that a very light sheet stock 95 may be employed in large sized units which carry a substantial load. The strengthening means for the tops of the units illustrated in Fig. 1 serve the additional purpose of breaking up cumulative expansion effects 100 in a direction lengthwise of the unit while the top shown in Fig. 8 is suitably stiffened but cumulative expansion across the top only is taken care of in a direction transverse to the unit by the longitudinal rib. The varying styles of ridges, etc. employed in 105 the side walls stiffen substantially the entire surface of those walls to prevent their being distorted or bent due to stresses which may arise in the event of that while the units are shaken, clinkers become wedged in between adjacent units. These strengthening 110 means, and particularly those illustrated in Fig. 8, give the side wall of the units great stiffness and rigidity even though the metal employed is quite thin.

115 What I claim:

1. In a grate bar, a removable finger bar 120 which comprises a single piece of sheet metal having a continuous one-piece top and side portions connected to the top along its edges and depending therefrom, said top being formed with at least one ridge extending from one boundary of the top to another, the top of said ridge constituting a fuel support, said side portions having spaced parts bent out of the plane of the metal and serving to stiffen the side portions.

2. In a grate bar, a removable finger bar 125 which comprises a single piece of sheet metal having a one-piece top and sides connected 130

- to the top along its edges and depending therefrom, said top being formed with a plurality of transverse ridges, the tops of said ridges constituting supporting means for fuel, said sides having spaced portions lying spaced inwardly from the edges thereof bent out of the plane of the metal to stiffen said sides.
3. In a grate bar, a removable finger bar which comprises a single piece of sheet metal having a top and sides connected to the top along its edges and depending therefrom, said top being transversely corrugated, said sides having spaced portions remote from the edges bent out of the plane of the metal to stiffen said sides.
4. In a grate bar, a removable finger bar which comprises a single piece of sheet metal having a top and sides connected to the top along its edges and depending therefrom, said top being formed with a plurality of transverse ridges and a longitudinal ridge intersecting said transverse ridges, said sides having spaced portions bent out of the plane thereof to form a plurality of rows of ribs to stiffen the sides.
5. In a grate bar, a removable finger bar which comprises a single piece of sheet metal having a top and sides connected to the top along its edges and depending therefrom, said top being formed with a plurality of transverse ridges separated by depressions, said ridges being so closely spaced as to maintain particles of fuel supported by said finger bar out of said depressions, said sides being formed with spaced portions distorted out of the plane thereof and lying spaced inwardly from the edges of said sides, said portions stiffening the sides.
6. In a grate bar, a removable finger bar which comprises a single piece of sheet metal formed to provide a fuel-supporting top and side walls connected to the top along its edges and extending downward therefrom, said side walls having portions deformed out of the plane thereof to stiffen said walls, said deformed portions extending at an angle to the vertical when the finger bar is in normal upright position.
7. In a grate bar, a removable finger bar which comprises a single piece of sheet metal formed to provide a fuel-supporting top and side walls connected to the top along its edges and extending downward therefrom, said side walls having portions deformed out of the plane thereof to stiffen said walls, said portions including elongated ribs extending at an angle to the vertical when the finger is in normal upright position.
8. In a grate bar, a removable finger bar which comprises a single piece of sheet metal formed to provide a fuel-supporting top and side walls connected to the top along its edges and extending downward therefrom, said side walls having portions deformed out of the plane thereof to stiffen said walls, said portions comprising elongated ribs extending at an angle to the vertical when the finger bar is in normal upright position.
9. In a grate bar, a removable finger bar which comprises a single piece of sheet metal formed to provide a fuel-supporting top and side walls connected to the top along its edges and extending downward therefrom, said side walls having portions deformed out of the plane thereof to stiffen said walls, said portions comprising ribs arranged end to end in lines and extending substantially across said walls at an angle to the vertical when the finger bar is in normal upright position.
10. In a grate bar, a removable finger bar which comprises a single piece of sheet metal formed to provide a fuel-supporting top and side walls connected to the top along its edges and extending downward therefrom, said side walls having portions deformed out of the plane thereof to stiffen said walls, said portions comprising two series of parallel ribs, the ribs of one series intersecting the other.
11. In a grate bar, a removable finger bar which comprises a single piece of sheet metal formed to provide a fuel-supporting top and side walls connected to the top along its edges and extending downward therefrom, said side walls having portions deformed out of the plane thereof to stiffen said walls, said portions comprising two series of parallel ribs, the ribs of one series intersecting the other, and the ribs of both series lying at an angle to the vertical when the finger bar is in normal upright position.
12. In a grate bar, a removable finger bar which comprises a single piece of sheet metal formed to provide a fuel-supporting top and side walls connected to the top along its edges and extending downward therefrom, said side walls having portions deformed out of the plane thereof to stiffen said walls, said portions comprising a series of ribs inclined to the vertical when the finger bar is in normal upright position.
13. In a grate bar, a removable finger bar having means for mounting the finger bar on a carrier, said finger bar comprising a single piece of sheet metal having a top and sides connected to the top along its edges, said top and sides defining a chamber, and said top and sides being formed with ridges extending substantially from one of the boundaries of the top and of the sides to another.
14. In a grate bar, a removable finger bar having means for mounting the finger bar on a carrier, said finger bar comprising a single piece of sheet metal having a top and sides connected to the top along its edges, said top and sides defining a chamber, and said top and sides being formed with strengthening means produced by deformation of the metal,

said means extending substantially throughout the surfaces of said top and sides.

15. In a grate bar, a removable finger bar which comprises a top and sides of sheet metal, said finger bar being hollow and each side having portions thereof bent out of the plane of the sheet and serving to stiffen said sides, said portions including elongated ribs extending at an angle to the vertical when the finger bar is in normal upright position.

16. In a grate bar, a removable finger bar which comprises a top and sides of sheet metal, said finger bar being hollow and the sides thereof having portions deformed out of the plane thereof to stiffen said walls, said portions including parallel elongated ribs extending at an angle to the vertical when the finger bar is in normal upright position.

In testimony whereof I affix my signature.
